UNITED STATES PATENT OFFICE.

EDWARD HENRY HIGBEE, OF ROODHOUSE, ILLINOIS.

RECTUM-SUPPORTER.

No. 807,169.

Specification of Letters Patent.

Patented Dec. 12, 1905.

Application filed May 16, 1905. Serial No. 260,646.

To all whom it may concern:

Be it known that I, EDWARD HENRY HIGBEE, a citizen of the United States, and a resident of Roodhouse, in the county of Greene and State of Illinois, have invented a new and Improved Rectum-Supporter, of which the following is a full, clear, and exact description.

The purpose of the invention is to provide a practical, light, and simple appliance especially adapted for the relief and cure of prolapsus of the rectum and hemorrhoids or piles and to so construct the appliance that it may be worn with comfort and may be partially removed in an expeditious and convenient manner when occasion may demand.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

25 Figure 1 is a perspective view of the complete appliance. Fig. 2 is a front elevation of one of the hooks employed. Fig. 3 is a vertical section through the belt and the rear hook, illustrating the manner in which a supporting-cord is attached to the hook; and Fig. 4 is a section through the body portion of the supporter and portions of the supporting-cords, other portions of the cords being shown in elevation.

35 The supporter consists, primarily, of a spherical or ball body A, adapted to be fitted to the rectum, a rear supporting-cord B, extending from the rear central portion of the ball-body, and two forward supporting-cords 40 C and D, which extend side by side from the forward central portion of said ball-body. All of the said parts are made of yielding or elastic rubber, and, as is shown at 10 in Fig. 4, the body and supporting-cords are preferably 45 molded or otherwise constructed in one piece.

In connection with the supporter just described a waist-belt 11 is provided, made of any suitable material, the ends whereof are connected by a buckle 12 or otherwise. Three 50 hooks E are carried by the belt, one located at each side of the front central portion of the belt and one hook at its rear center, as is illustrated in Fig. 1. These hooks are especially adapted for quick and convenient engagement 55 with or detachment from the supporting-cords

B, C, and D and are usually made each from one piece of wire of suitable gage, comprising a skeleton body 13, a skeleton bill 14, and a shank 15, extending down from the body, said shank having two eyes 16 and 17 formed 60 therein, one above the other, as is particularly shown in Fig. 2. The manner in which the attachment is made between the supporting-cords B, C, and D, and the hooks E is clearly illustrated in Figs. 1 and 3, wherein 65 the elastic cords are shown as passed through the lower eye 16 of the hook and then through the upper eye 17, being adjustably held in place by a bend in the cord between the eyes and the frictional engagement of the cord with 70 the eyes.

It is evident that the cords may be quickly and conveniently attached to the hooks and as speedily and conveniently disconnected and that the cords may be adjusted in the hooks 75 to suit the convenience of the wearer of the appliance.

The back cord B leads up to the central portion of the back of the wearer and the forward cords upward at the groins for attachment to 80 the belt in the manner described. The rear supporting-cord B is twice the strength of each of the cords C and D used in front, which gives an equal, positive, and continuous pressure in all directions against the anus and provides the greatest convenience in going to 85 stool simply by unhooking the rear cord from the back of the waist-belt.

This supporter is very simple of adjustment and attachment to the waist-belt and is adjustable to any size of person.

Having thus described my invention, I claim as new and desire to secure by Letters Patent—

1. A rectum - supporter, consisting of a spherical body, a rear cord integral with the 95 body and leading from the rear central portion thereof and front cords which lead side by side from the front central portion of the said spherical body, the said cords and spherical body being constructed of elastic rubber 100 and the rear cord being of double the strength of each of the front cords.

2. A belt, hooks carried by the belt, and a rectum - supporter consisting of a spherical body, a rear cord leading from the central 105 portion of the spherical body at the rear, and forward cords leading from the forward central portion of the spherical body, all of the cords and the body being constructed of elastic rubber, the rear cord being of greater 110

strength than either of the forward cords, and means for removably and adjustably connecting the cords with the hooks.

3. The combination with a waist-belt and 5 hooks carried thereby, said hooks being provided with downwardly-extending shanks having eyes therein arranged one above the other, of a supporter, consisting of a ball-body, a rear cord extending from the rear central portion of said ball-body, and forward cords extending side by side from the forward central portion of the body, all of the cords and the body being of elastic rubber but the rear cord being of greater strength than either of the 10 other cords, the ends of the said cords being laced through the eyes of the said hooks, as described.

4. A rectum - supporter, consisting of a waist-belt, a ball-body, a rear cord extending

from said ball-body at its rear, forward cords 20 extending side by side from the ball-body at its front, the cords and body being integrally constructed of a yielding material, the rear cord being of greater strength than either of the forward cords, and means for removably 25 and adjustably connecting the ends of said cords in said belt.

5. A rectum - supporter, comprising a spherical body having integral therewith a rear and two forward cords, the body and 30 cords being of elastic material.

In testimony whereof I have signed my name to this specification in the presence of two subscribing witnesses.

EDWARD HENRY HIGBEE.
